VARIABLE CAPACITY PUMP

Joseph F. Joy, Claremont, N. H., assignor to Sullivan Machinery Company, a corporation of Massachusetts

Application September 7, 1938, Serial No. 228,811

11 Claims. (Cl. 103—161)

This invention relates to variable capacity pumps, and more particularly, but not exclusively, to improvements in variable capacity pumps of that character which is especially designed for use as a driving element of a variable speed hydraulic power transmission.

An object of the present invention is to provide an improved variable capacity pump having improved means for varying the pump displacement. Another object is to provide an improved variable capacity pump of the reciprocating piston type having improved means for varying the piston stroke, to vary the displacement of the pump. A further object is to provide an improved variable stroke pump having improved stroke varying means for the pump piston designed so that the capacity of the pump may be varied smoothly from zero to a maximum capacity. A still further object is to provide an improved variable stroke actuating means for a pump piston embodying means adjustable at will to vary the piston stroke. Still another object is to provide an improved stroke varying means operatively connected to the piston for effecting reciprocation of the latter and having means for varying the angular relation of certain of the elements thereof to vary the action of the stroke effecting means. Yet another object is to provide an improved valve mechanism for such a pump. These and other objects and advantages of the invention will, however, hereinafter more fully appear.

In the accompanying drawings there are shown for purposes of illustration one form and a modification which the invention may assume in practice.

In these drawings—

Fig. 1 is a top plan view of an illustrative embodiment of the improved pump, with the top portion of the casing omitted and a part broken away.

Fig. 2 is a side elevational view of the pump shown in Fig. 1, with a portion of the casing structure shown in vertical section.

Fig. 3 is a view in longitudinal vertical section taken substantially on line 3—3 of Fig. 1.

Fig. 4 is a longitudinally extending horizontal sectional view taken substantially on line 4-4 of Fig. 2.

Fig. 5 is a cross sectional view taken substantially on line 5-5 of Fig. 3.

Fig. 6 is a fragmentary sectional view taken in the plane of Fig. 4, showing parts in a different position.

Fig. 7 is a cross sectional view taken substantially on line 7—7 of Fig. 3.

Fig. 8 is a view similar to Fig. 3, showing a modified form of construction.

Fig. 9 is a horizontal sectional view, taken substantially on line 9-9 of Fig. 8, with parts in elevation. 5

Fig. 10 is a cross sectional view taken on line 10-10 of Fig. 8.

In both the illustrative embodiment of the invention shown in Figs. 1 to 7, inclusive, and the modification shown in Figs. 8, 9 and 10, the improved pump, generally designated 1, is of the variable capacity type especially designed for use as the driving element of a variable speed power transmission means, and is particularly adapted for use with a variable speed hydraulic motor for supplying fluid under pressure in variable quantities to the latter. It will be understood, however, that the improved pump is of general application and may be associated with various forms of hydraulic power transmissions. 20

As shown in Figs. 1 to 7, inclusive, the improved pump 1 is arranged in a chamber 2 formed in a casing 3, and this casing chamber is adapted to contain a fluid, preferably a liquid such as oil. The pump comprises a rotary cylindric body 4 having an integral drive shaft 5 adapted to be driven from any suitable source of power and journaled within the casing chamber by a ball bearing 6 supported by a bearing bracket 7 integral with the casing 3. The rotary pump body is journaled at its opposite end on an alined ball bearing 8 supported by a stub shaft 9 fixed within the outer casing wall, the latter being prefer- 35

ably in the form of a detachable cover plate 10. It will thus be seen that the pump is rotatable as a unit within the casing about a horizontal axis, when the drive shaft is driven. The pump body 4 is formed with a transverse cylinder bore 40 11 arranged with its longitudinal axis at right angles to the axis of rotation of the pump body and containing a reciprocable pump piston 12 of the double-acting type having piston head portions at its opposite ends closely fitting the walls 45 of the cylinder bore. Fixed in a stationary position with respect to the casing 3, as by a pin 13 secured to the bearing bracket 4, is a valve block 14 having opposed arcuate grooves or slots 15 and 16, the former connected to an intake pipe 17 50 and the latter to a discharge pipe 18. The intake pipe 17 is submerged in the oil within the casing chamber 2, as shown in Fig. 3, and is provided with a suitable strainer 19 for preventing entry of dirt to the intake pipe. The plane end face 20 55

of the rotary pump body 4 has a close running fit with an abutting plane end face 21 of the stationary valve block 14, and, if desired, any suitable sealing means, such as a sealing ring, may be provided to prevent leakage between the relatively movable abutting surfaces. The rotary pump body 4 has passages 22 and 23 respectively communicating with the remote ends of the cylinder bore 11, as shown in Figs. 4 and 6, and 10 communicable through ports 24 and 25, respectively, with the supply and exhaust grooves 15 and 16 in the valve block. As the pump body 4 rotates relative to the stationary valve block 14, the ports 24 and 25 move successively into communication with the supply and exhaust grooves, and as the piston 12 reciprocates within its bore, fluid is drawn in from the intake groove and thereafter discharged through the discharge groove, in an obvious manner.

20 Now referring to the improved means for actuating the piston and for varying the piston stroke, it will be observed that the piston 12 has rack teeth 26 formed thereon and meshing with the teeth of a gear segment 27 formed integral with a pivoted block 28. This pivoted block 28 is mounted on a transverse pivot pin 29 arranged at right angles to the axis of rotation of the pump body and supported at its ends within bushings 30 supported within laterally spaced projections 31 integral with the pump body. The pivoted block is arranged between these spaced projections, as shown in Fig. 5. It therefore will always, when oscillated about its pivot, swing in the diametric planes in which the piston moves.

30 The actuating means for oscillating the pivoted block to cause piston reciprocation may now be described. Arranged in right angular relation to the pin 29 and extending through aligned bores 32 and 33 formed in the pin 29 and pivoted block 28, respectively, is a pin 34 pivotally connected at its ends at 35 to a ring bearing 36. The ring bearing 36 is preferably composed of two mating parts to facilitate assembly, and the two parts thereof cooperate to provide an annular flange 37 rotatably engaged in an annular groove 38 provided by a trunnion-providing element 39 and a cooperating retaining annulus 40 secured, as by screws 41, to the element 39. The element 39, as viewed in Fig. 5, is itself generally 40 in the form of an annulus and is pivotally mounted at 42 through trunnions supported in upper and lower bearing brackets 43, herein preferably supported by the detachable cover plate 10 of the casing. The element 39 is swingable horizontally about a vertical axis within its pivotal bearing mountings and has an integral projecting lever 44 engaged in a transverse rectangular slot 45 formed in a control shaft 46. This control shaft is slidably mounted at 47 in a bearing boss 48 formed integral with the bearing bracket 7, and its outer portion is threaded at 49 for threaded engagement with a nut 50. This nut is rotatably mounted in aligned ball thrust bearings supported within a bearing bracket 52, herein preferably formed integral with the detachable cover plate 10. A hand wheel 53 integral with the nut 50 is provided for manually rotating the latter to effect axial adjustment of the control shaft 46. Rotation of the control shaft during such axial adjustment is prevented by the lever 44 engaging the walls of the slot 45 in the control shaft. The co-operating threads on the nut and control shaft are self-locking and positively lock the control shaft in its adjusted position. The rectangularly

related axes of the pins constitute pivotal axes, since the ring bearing and gear-segment-block rock about the axes of the pins as the pump-parts revolve and the trunnion element 39 is tilted.

In the modified construction disclosed in Figs. 8, 9 and 10, the pump cylinder and piston structure and the means for effecting a variable piston stroke are essentially the same as those described above (like parts being designated by like reference characters), with the exception that the drive shaft for the cylindric pump body is located at the same end of the pump as the stroke-varying-means for the pump piston, and the pump valve mechanism is arranged at the end of the pump opposite from the drive shaft. In this construction, the cylindric pump body is indicated at 55 and the drive shaft at 56, and the valve mechanism is generally designated 57. The bore 11 containing the reciprocating pump 20 piston 12 is fitted with a liner sleeve 58 having flanged ends and held in position by threaded plugs 59 engaging the flanged liner ends, as shown in Fig. 9. The cylindric pump body is journaled for rotation within the casing chamber 25 2 by a ball bearing 60 supporting the shaft 56 and a ball bearing 61 supporting a cylindric valve member 62 secured, as by a key, within a bore 63 in the pump body, these bearings being suitably supported within the end walls of the 30 casing. The member 62 is formed with a conically-shaped bore 64 receiving a tapered valve plug 65 fixed to the detachable cover plate of the outer casing wall. This valve plug has a tight running fit with the walls of the bore 64, 35 and the space at the inner end of the valve plug is vented by a passage 66 and an annular groove 67 on the liner sleeve communicating with the interior of the casing chamber. The valve plug has transverse grooves 68 and 69 communicating with passages 70 and 71 respectively, and the passage 70 is connected to a supply pipe 72 submerged within the liquid in the casing chamber, while the passage 71 is connected to a discharge pipe 73. The member 62 has radial ports 74 45 and 75 communicating with the valve plug bore in the same transverse planes as the grooves 68 and 69 and communicating respectively with passages 76 and 77 in the pump body. The passages 76 and 77 have ports communicating with 50 the remote ends of the cylinder bore 11, and the liner sleeve has perforations in registry with these ports. As the pump body and the valve member 62 rotate relative to the stationary valve plug 65, the ports 74 and 75 in the valve member 62 move successively into communication with the supply and exhaust grooves 68 and 69, and as the piston 12 is reciprocated, liquid is drawn in from the supply groove and thereafter discharged through the discharge groove, in an 60 obvious manner. It will be evident that the tight running fit between the tapered valve plug and its bore substantially eliminates leakage between the parts. Otherwise, this embodiment of the invention is the same as that above described.

The mode of operation of the embodiment of the improved variable stroke pump disclosed in Figs. 1 to 7, inclusive, will be clearly apparent from the description given. When the drive shaft 5 is driven in any suitable manner and 70 the parts are in the neutral position shown in Fig. 4, the pump body 4 is rotated, rotating therewith as a unit the parts 28, 36 of the stroke varying means, and, due to the fact that the pin 34 will rotate with its longitudinal axis confined in 75

a transverse plane perpendicular to the axis of rotation of the rotor of the pump body, rotation of the pump body will not cause piston reciprocation, and the piston will remain stationary in its centrally located position within the cylinder bore, and no liquid displacement from the pump will occur. When it is desired to effect liquid displacement, the operator may adjust the nut hand wheel 53, thereby to move the control shaft 46 axially, and swing the element 39 horizontally about its pivotal mounting to vary the angular relation of the plane traced by the pin 34, with respect to the transverse vertical plane including the axis of the pin 29. It will be evident that the axis of the pin 34 and the axis of the piston 12 will be continuously maintained in the same plane with each other but that their relation to each other will vary between parallelism and the maximum angle equal in angularity to the dihedral angle between the planes traced by the axis of the piston 12 and by the axis of the pin 34, and in view of the relation of the block 28 to the ring bearing 36 there will be effected a reciprocatory motion of the piston 12 in its cylinder, the piston being in central position in its cylinder when the axis of the pin 34 and the axis of the piston 12 are parallel to each other. By varying the angular position of the element 39 about its pivot, the piston stroke may be varied, consequently varying the displacement of the pump. When the trunnion element 39 is tilted out of a transverse vertical plane, as shown in Fig. 6, and the pump parts are rotating about the axis of the shaft 5 upon driving by the latter, the ring bearing 36 revolves in the annular groove 38 in the relatively stationary element 39 and as a result the ring bearing 36 has a slight rocking movement about the axis of the pivot pin 34 relative to the block 28. Simultaneously the ring bearing 36 and block 28 have a rocking movement about the axis of the pivot pin 29 and as a result the gear segment 27 swings back and forth to effect reciprocation of the pump piston. The rectangularly related axes of the pivot pins provide a universal connection between the gear segment and the trunnion element 39 so that when the element 39 is tilted into different positions, the axis of swinging movement of the gear segment 27 is varied, resulting in a corresponding variation in the reciprocatory strokes of the pump piston. When the parts are in the full line position shown in Fig. 6, the pump piston 12 is in its maximum stroke position, and it will be evident that the element 39 may be swung into any desired intermediate position between that shown in Fig. 6 and that shown in Fig. 4, to vary the piston stroke from a maximum to zero. As above mentioned, as the pump body 4 rotates relative to the stationary valve block 14, the ports 24, 25 are brought successively into communication with the supply and discharge grooves 15 and 16, so that fluid is drawn into the cylinder bore from the supply groove and discharged from the cylinder bore through the discharge groove. When the element 39 is swung about its pivotal mounting from the position shown in Fig. 6 to the dotted line position shown in that figure, the liquid flow through the pump is reversed so that liquid is discharged from the groove 16 to the groove 15, at that time. The mode of operation will be very clear when it is borne in mind that the piston 12 will be in mid-stroke position each time the pin 34 is aligned with the pivotal axes of the element 39, a rela-

tive position assumed twice in each cylinder member rotation irrespective of the position of the lever 44.

The mode of operation of the modified construction disclosed in Figs. 8, 9 and 10 is essentially the same as that above described in that when the drive shaft 56 is driven in any suitable manner and the parts are in their neutral position shown in Fig. 9, the pump body is rotated, rotating therewith as a unit the parts of the stroke-varying-means, and, due to the position of the parts, rotation of the pump body will not cause reciprocation of the pump piston, and the piston will remain stationary in its midway position within the cylinder bore, and no liquid displacement from the pump will occur. When it is desired to effect liquid displacement, the operator may adjust the stroke-varying-mechanism, in the manner described above, thereby to swing the element 39 horizontally about its pivotal mounting to vary the angular relation of the plane traced by the pin 34, with respect to the transverse vertical plane including the axis of the pin 29, and as a result, as above explained, the piston is reciprocated back and forth within the cylinder bore. It will again be evident that by varying the angular position of the element 39 about its pivot, the piston stroke may be varied, consequently varying the pump displacement all in the manner described above. The liquid is drawn into the pump cylinder from the pipe 12 into the passage 70 and groove 68 and thence to the cylinder-entering-ports and is discharged from the cylinder through the groove 69, passage 71 and pipe 73. Any leakage of liquid past the surfaces of the plug and the bore walls is discharged back to the liquid chamber through passage 66 and groove 67. Otherwise, the modified embodiment of the invention operates in a manner similar to that above described.

As a result of this invention, it will be noted that an improved variable stroke pump is provided having improved means for varying the stroke of the pump piston. It will further be noted that by the provision of the piston reciprocating means disclosed, the capacity of the pump may be varied by imperceptible degrees from zero to a maximum capacity in an extremely simple manner. Furthermore, by the provision of the improved piston reciprocating means, the piston stroke may not only be varied in an extremely simple manner, but the parts are also of a rugged and durable construction well adapted to withstand the demands of service. It will also be evident that by the provision of the improved valve mechanism, leakage between the relatively rotatable valve parts is reduced to a minimum. Other uses and advantages of the improved variable stroke pump will be clearly apparent to those skilled in the art.

While there are in this application specifically described one form and a modification which the invention may assume in practice, it will be understood that this form and modification of the same are shown for purposes of illustration and that the invention may be further modified and embodied in various other forms without departing from its spirit or the scope of the appended claims.

What I claim as new and desire to secure by Letters Patent is:

1. In a pump, the combination of a rotary pump body having a transverse cylinder bore, a pump piston reciprocable within said cylinder

- bore, means for rotating said pump body, and means including piston reciprocating elements rotatable with said pump body and operatively connected to said piston for reciprocating the latter as said pump body rotates, said piston reciprocating elements comprising a rack formed on said piston and a pivotally mounted gear segment having its teeth meshed with the rack teeth and means for swinging said gear segment about its pivot.
2. In a variable stroke pump, the combination of a rotary pump body having a transverse cylinder bore, a pump piston reciprocable within said cylinder bore, means for rotating said pump body, means including piston reciprocating elements rotatable with said pump body and operatively connected to said piston for reciprocating the latter as said pump body rotates, said piston reciprocating elements comprising a rack formed on said piston and a pivotally mounted gear segment having its teeth meshed with the rack teeth and means for swinging said gear segment about its pivot, and means for varying the range of swinging movement of said gear segment.
3. In a variable stroke pump, the combination of a rotary pump body having a transverse cylinder bore, a pump piston reciprocable within said cylinder bore, means for rotating said pump body, means including elements rotatable with said pump body and operatively connected to said piston for reciprocating the latter as said pump body rotates, said piston reciprocating elements comprising a rack formed on said piston, a swingable gear segment having its teeth meshed with the rack teeth, means for pivotally mounting said gear segment on the pump body, a rotatable ring bearing pivotally connected to said gear segment on an axis arranged at right angles to said pivotal axis of said gear segment, and means for varying the range of swinging movement of said gear segment comprising trunnion means within which said ring bearing is rotatably mounted for pivotal movement and swingable about its pivot for tilting said ring bearing.
4. In a variable stroke pump, the combination of a rotary pump body having a transverse cylinder bore, a pump piston reciprocable within said cylinder bore, means for rotating said pump body, means including elements rotatable with said pump body and operatively connected to said piston for reciprocating the latter as said pump body rotates, said piston reciprocating elements comprising a rack formed on said piston, a pivotally mounted gear segment having its teeth meshed with the rack teeth, and means for varying the range of swinging movement of said gear segment including an element having a pivotal connection with said gear segment on an axis at right angles to the pivotal axis of said gear segment.
5. In a variable stroke pump, the combination of a rotary pump body having a cylinder bore arranged with its longitudinal axis lying in a plane perpendicular to the axis of rotation of the pump body, a pump piston reciprocable in said cylinder bore, means for rotating said pump body, means including elements rotatable with said pump body and operatively connected to said piston for reciprocating the latter as said pump body rotates, said piston reciprocating means comprising a swingable member engaging said piston and swingable to effect piston reciprocation, a pivotal mounting for said swingable member on said pump body, and means for varying the range of swinging movement of said swingable member including an element having a pivotal connection with said swingable member on an axis at right angles to the pivotal axis of said swingable member, the pivotal axes of said swingable member and said pivotal element being disposed at right angles to the axis of rotation of said pump body.
6. In a variable stroke pump, the combination of a rotary pump body having a cylinder bore arranged with its longitudinal axis lying in a plane perpendicular to the axis of rotation of the pump body, a pump piston reciprocable in said cylinder bore, means for rotating said pump body, means including elements rotatable with said pump body and operatively connected to said piston for reciprocating the latter as said pump body rotates, said piston reciprocating means comprising a swingable member engaging said piston and swingable to effect piston reciprocation, a pivotal mounting for said swingable member on said pump body, and means for varying the range of swinging movement of said swingable member including an element having a pivotal connection with said swingable member on an axis at right angles to the pivotal axis of said swingable member and a pivoted trunnion operatively connected to said pivotal element and within which the latter is rotatably mounted, the pivotal axes of said swingable member and said trunnion being disposed at right angles to the axis of rotation of said pump body.
7. In a variable stroke pump, the combination of a rotary pump body having a cylinder bore arranged with its longitudinal axis lying in a plane perpendicular to the axis of rotation of the pump body, a pump piston reciprocable in said cylinder bore, means for rotating said pump body, means including elements rotatable with said pump body and operatively connected to said piston for reciprocating the latter as said pump body rotates, said piston reciprocating means comprising a swingable member engaging said piston and swingable to effect piston reciprocation, a pivotal mounting for said swingable member on said pump body, and means for varying the range of swinging movement of said swingable member including an element having a pivotal connection with said swingable member on an axis at right angles to the pivotal axis of said swingable member and a pivoted trunnion operatively connected to said pivotal element and within which the latter is rotatably mounted, the pivotal axes of said swingable member and said trunnion being disposed at right angles to the axis of rotation of said pump body, and means operable at will for adjusting said trunnion about its pivot to vary the angular relation of said rotatably mounted element and for locking said trunnion in its adjusted positions.
8. In a pump, the combination of a rotary pump body having a cylinder bore arranged with its longitudinal axis lying in a plane perpendicular to the axis of rotation of the pump body, a pump piston reciprocable in said cylinder bore, means for rotating said pump body, means including elements rotatable with said pump body and operatively connected to said piston for reciprocating the latter as said pump body rotates, said piston reciprocating elements comprising a swingable member pivotally mounted on said pump body on an axis at right angles to the axis of rotation of said pump body and engaging said piston, and means for effecting swinging move-

ment of said swingable member back and forth as said pump body rotates to effect piston reciprocation comprising a rotatable member having a pivotal connection with said swingable member on an axis at right angles to the axis of pivotal movement of said swingable member.

9. In a variable stroke pump, the combination of a rotary pump body having a cylinder bore arranged with its longitudinal axis lying in a plane perpendicular to the axis of rotation of the pump body, a pump piston reciprocable within said cylinder bore, means for rotating said pump body, means including elements rotatable with said pump body and operatively connected to said piston for reciprocating the latter as said pump body rotates, said piston reciprocating elements comprising a swingable member pivotally mounted on said pump body on an axis at right angles to the axis of rotation of said pump body and engaging said piston, means for effecting swinging movement of said swingable member back and forth as said pump body rotates to effect piston reciprocation comprising a rotatable member having a pivotal connection with said swingable member on an axis at right angles to the axis of pivotal movement of said swingable member, and means for adjusting said rotatable member to vary the range of pivotal movement of said swingable member comprising a pivotally mounted member on which said rotatable member is mounted and means for adjusting said pivotally mounted member into different angular positions about its pivot.

10. In a variable stroke pump, a rotary pump body having a cylinder bore arranged with its longitudinal axis lying in a plane perpendicular to the axis of rotation of the pump body, a pump piston reciprocable within said cylinder bore, means for rotating the pump body, means including piston reciprocating elements rotatable with said pump body and operatively connected to said piston for reciprocating the latter as said

pump body rotates, said piston reciprocating elements comprising a piston reciprocating element pivotally mounted on said pump body and engaging said piston, a tiltable element pivotally mounted on a relatively fixed axis and relative to which said pump body is rotatable, the pivotal axes of said piston reciprocating element and said tiltable element being arranged at right angles to the axis of rotation of the pump body, an operative connection between said tiltable element and said pivotally mounted element, and means for tilting said tiltable element into different positions about its pivot to vary the range of swinging movement of said pivotally mounted element, thereby to vary the piston stroke. 15

11. In a variable stroke pump, a rotary pump body having a cylinder bore arranged with its longitudinal axis lying in a plane perpendicular to the axis of rotation of the pump body, a pump piston reciprocable within said cylinder bore, 20 means for rotating the pump body, means including piston reciprocating elements rotatable with said pump body and operatively connected to said piston for reciprocating the latter as said pump body rotates, said piston reciprocating elements comprising a piston reciprocating element pivotally mounted on said pump body, a tiltable element pivotally mounted on a relatively fixed axis and relative to which said pump body is rotatable, the pivotal axes of said piston reciprocating element and said tiltable element being arranged at right angles to the axis of rotation of the pump body, an operative connection between said tiltable element and said pivotally mounted element including an element having a 35 pivotal connection with said pivotally mounted element on an axis at right angles to the pivotal axis of said pivotally mounted element, and means for tilting said tiltable element about its pivot to vary the range of swinging movement 40 of said pivotally mounted element, thereby to vary the piston stroke.

JOSEPH F. JOY.
